TELEPHONE ATTACHMENT FOR HOLDING A
CALENDAR, MEMO-PAD AND PENCIL

George A. Aro, 2925 18th Ave. N., Minneapolis, Minn.

Filed Apr. 2, 1965, Ser. No. 84,589

Term of patent 14 years

(Cl. D26—14)

This application is a continuation-in-part of my co-pending application Serial Number D. 79,138, filed March 20, 1964, and now abandoned.

I claim:

The ornamental design for a telephone attachment for holding a calendar, memo-pad and pencil, substantially as shown and described.
